UNITED STATES PATENT OFFICE.

ACHILL BIPPART, OF NEWARK, NEW JERSEY.

DESIGN FOR A BACK AND SHANK FOR BUTTONS OR STUDS.

SPECIFICATION forming part of Design No. 29,225, dated August 16, 1898.

Application filed December 24, 1897. Serial No. 663,437. Term of patent 14 years.

To all whom it may concern:

Be it known that I, ACHILL BIPPART, a citizen of the United States, residing at Newark, county of Essex, State of New Jersey, have 5 invented a certain new and useful Design for a Back and Shank for Buttons or Studs, fully described and represented in the following specification and the accompanying drawings, forming a part of the same.

10 The present design relates to the shank and back of a cuff-button or collar-stud.

In the present design the back is of dish shape entirely open upon the upper side and formed with curled flange at the edge, and 15 the shank is of oval form in cross-section, with edges of ogee shape joined to the back by a continuous curve. The shank is of thin substance with internal cavity, which is flared outwardly where the shank is joined to the 20 back.

The design is shown in the accompanying drawings, in which—

Figure 1 is a plan of the button back and shank, illustrating my design. Fig. 2 is a 25 central longitudinal section of the button through the width of the shank, and Fig. 3 is a central longitudinal section through the thickness of the shank.

B designates the dish-shaped back with 30 edge turned up upon its inner side. The back is concave and open upon the upper side, and the shank A is of oval flattened form, as shown in Fig. 1, with rounded edges having an ogee profile joined to the back by curves C. The 35 sections in Figs. 2 and 3 show the thickness

of the substance of the shank, which substance is extended in a continuous line from the upturned edge of the back B through the curves C and the ogee contour of the edges to the top of the shank, which presents a flat 40 circular seat, as shown in Figs. 1 and 2. The line at each edge of the shank forms a continuous reversed or ogee curve upon the rounded edges of the shank, as exhibited in Fig. 2. The cavity A' within the shank is of 45 the same contour as the exterior of the cavity and is flared outwardly where the shank is joined to the back by the curves C.

The essential features of my design are the oval cross-section of the shank, the dish shape 50 of the back, with curled flange upon its inner edge, the connection of the edges of the shank with the back by the continuous curved line, (which is extended from the top of the shank through the ogee curves upon its edges to the 55 curled edge of the back,) and the cavity A within the shank, having the same form as the exterior of the shank and flared outwardly where it is joined to the back by the curves C.

Having thus defined my invention, what I 60 claim is—

The design for back and shank of button or stud, as herein described and shown.

In testimony whereof I have hereunto set my hand in the presence of two subscribing 65 witnesses.

ACHILL BIPPART.
